CLAIM

The ornamental design for a beverage dispenser, substantially as shown and described.

DESCRIPTION

FIG. 1 is a perspective view of a beverage dispenser showing my new design, the broken lines being for illustrative purposes only;

FIG. 2 is a bottom perspective view thereof;

FIG. 3 is a left side elevational view thereof; and
FIG. 4 is a cross-sectional view taken along the lines 4—4 of FIG. 3.

FIG. 1

FIG. 2

FIG. 3

FIG. 4
